UNITED STATES PATENT OFFICE.

JOHN P. WEIS, OF BROOKLYN, NEW YORK, ASSIGNOR, BY MESNE ASSIGNMENTS, TO
METROPOLITAN SEWING MACHINE COMPANY, A CORPORATION OF NEW YORK.

NEEDLE-CLAMP FOR SEWING-MACHINES.

No. 914,325.

Specification of Letters Patent.

Patented March 2, 1909.

Original application filed June 5, 1903, Serial No. 160,207. Divided and this application filed August 17, 1903.
Serial No. 169,685.

To all whom it may concern:

Be it known that I, JOHN P. WEIS, a citizen of the United States, residing in Brooklyn, county of Kings, and State of New York, 5 have invented a new and useful Improvement in Needle-Clamps for Sewing-Machines, of which the following is a description.

This invention relates to sewing machines, and more particularly to means for securely 10 holding the needle firmly and properly in position for coöperation with the looper.

Specifically, the invention relates to needle-clamps by means of which a needle can be quickly and accurately adjusted in, or 15 relatively to, a needle-bar.

The objects of my invention are to provide a simple and cheap needle-clamp for holding the needle to the bar; to provide a needle-clamp by means of which the needle can be 20 firmly held in place; and to provide a needle-clamp by which the needle can be quickly placed in position and accurately adjusted.

With these objects in view, and others of importance which will appear during the 25 course of this description, my invention consists of the parts, features and combinations hereinafter described and claimed.

In the drawings forming part of this specification: Figure 1 shows in front elevation 30 sufficient of the arm of a sewing-machine to illustrate the application of my invention, the clamp being shown applied to the needle-bar; Fig. 2 shows the needle-clamp in elevation applied to the needle-bar, the lower end 35 only of the latter being shown; Fig. 3 is a side elevation of the parts of Fig. 2; Fig. 4 is a longitudinal section on line 4—4 of Fig. 2; and Fig. 5 is a cross-section on line 5—5 of Fig. 2.

40 A, is the frame of any ordinary sewing-machine; B, the needle-bar operating lever, pivoted to the frame, operated in any suitable manner, and connected to the needle-bar by the usual link C.

45 The needle-clamp consists of the angular bar or lever 1, pivoted at 2, to the needle-bar 3, and partially embracing the lower end of the latter. The lever 1, at its upper end, is provided with the boss 4, transversely bored 50 and screw-threaded for the reception of the clamp-screw 5. The lower end of the lever 1, is provided with the transverse pin or short bar 7. The needle-bar has a longitudinal bore 8, as usual, for the reception of the nee-

dle 9, which stem is slabbed on one side at 10. 55 The needle-bar is transversely cut at 11, for the reception and play of the bar 7, and at a distance above said cut 11, is smooth bored at 12, for the reception of the smooth end of the clamp-screw 5. 60

The lever 1, it will be seen in Fig. 5, generally speaking, is made to conform to the shape of the needle-bar; but, this is not of the essence of my invention, because the spirit of my invention would be involved 65 and the objects thereof accomplished by making the lever in simple form and providing the same with two contact points for engagement with the needle at two separate points of its shank. 70

It will now be clear that after the stem of the needle is inserted in the end of the needle-bar, and the screw 5, is turned, by manipulating its knurled head 13, until its smooth end 14, engages the upper end of the stem 75 of the needle, the clamp will have its bar 7, forced against the lower portion of the shank of the needle. This places firm pressure upon the needle-shank at two separated points and prevents even the slightest 80 movement of the needle either longitudinally or axially. The construction just described also enables the needle to be always accurately set without any care on the part of the operator, inasmuch as when the bar 85 7, engages the needle-shank or stem, the latter will be immediately turned and properly set, thus avoiding the necessity for care when the stem is inserted in the bar; and if said stem is thus inserted with its rounded 90 portion adjacent the bar 7, it will be instantly manifest to the operator and he has simply to turn the needle until its slabbed side engages the bar 7, when the needle will no longer be able to turn. Moreover, when 95 the screw 5, is set with its end against the slabbed side of the stem of the needle, it will be impossible for the latter to turn, and the tighter the screw is set the tighter the bar 7, will engage the needle-stem. Hence, my 100 construction provides a simple and effective clamp and one which is easily manipulated and requires no care on the part of the operator in setting the needle properly in the machine. The pivot pin 2, in this form of 105 my invention, is shown passing through ears or lugs 15, formed on the lever 1, and also passing through a hole drilled in the needle-

bar,—see Figs. 3 and 4; but, various changes in construction can be made within the spirit and scope of my invention. Moreover, it will be clear that I have provided a 5 needle-clamp which has a duplex bearing on the shank of the needle, and that this bearing is produced by manipulating but a single element of the clamp. All these are important features of my invention and upon them

10 I desire to lay stress.

This application is a division of my application No. 160,207, filed June 5, 1903.

Having thus described my invention what I claim and desire to secure by Letters Patent is:

15 1. A needle-clamp for sewing machines comprising a supporting bar longitudinally bored for the reception of the needle-stem, a lever pivoted to the bar, and means carried by the lever for contact with the needle-stem at separate points, the lever pivot and contact means being disposed on opposite sides of said bore and being thus capable of operation to bind said stem against said bar.

20 2. In combination with a needle having a stem with a flattened portion, a needle-clamp comprising a needle-bar longitudinally bored at one end for reception of said stem, a lever pivoted to said needle-bar by a pin 30 extending transversely thereof, and means carried by the lever for coöperating with the flattened portion of said stem whereby to bind said stem against said bar within its bore and simultaneously properly position 35 the needle in the bar.

25 3. A needle-clamp for sewing machines comprising a supporting bar, and a lever pivoted to the bar having a plurality of contact devices for engaging the needle-stem 40 and binding the latter against the bar, and one of said contact devices being movable relatively to said lever.

45 4. A needle-clamp for sewing machines comprising a supporting bar, and a lever pivoted to the bar having a plurality of contact devices for engaging the needle-stem

and binding the latter against the bar, and one of said contact devices having means for engaging said lever and forcing another of said devices into engagement with the 50 needle-stem.

5. A needle-clamp for sewing machines including among its essential elements a lever of the first order having contact devices on opposite sides of its pivot, and means whereby one of said contact devices may be adjusted relatively to the lever.

6. A needle-clamp for sewing machines including among its essential elements a lever of the first order having a plurality of 60 contact devices, and means whereby when one of said devices is manipulated to engage the stem of the needle another will also be caused to engage the needle-stem.

7. A needle-clamp for sewing machines 65 comprising a supporting bar longitudinally bored for the reception of the needle-stem, said bar being also transversely cut and transversely bored, a lever pivoted to the bar in rear of the longitudinal bore, and 70 means carried by the lever for entering the transverse bore and the cut for engaging the needle-stem and binding the same against the bar.

8. A needle-clamp for sewing machines 75 comprising a supporting bar, a lever of the first order pivoted to said bar, a plurality of contact devices for engaging the stem of the needle, one of which is fixed to the lever and another of which is adjustable relatively to 80 the lever, and means supported by the lever for actuating the adjustable contact devices to cause the same to engage the needle-stem and thereby simultaneously cause the said fixed device to also engage the needle-stem. 85

In testimony whereof I have hereunto signed my name in the presence of two subscribing witnesses.

JOHN P. WEIS.
